CLAIM

The ornamental design for an arm tunnel pillow, as shown and described.

DESCRIPTION

FIG. 1 is a perspective view of the arm tunnel pillow of the invention;

FIG. 2 is a front elevational view of the arm tunnel pillow of FIG. 1, the opposite side being a mirror image thereof;

FIG. 3 is a left side view of the arm tunnel pillow of FIG. 1, the opposite side being a mirror image thereof;

FIG. 4 is a bottom plan view of the arm tunnel pillow of FIG. 1; and,

FIG. 5 is a top plan view of the arm tunnel pillow of FIG. 1.
